UNITED STATES PATENT OFFICE

FRANZ NEUDORF, OF HORNDEAN, MANITOBA, CANADA.

RAIL-JOINT.

1,217,622.

Specification of Letters Patent. Patented Feb. 27, 1917.

Application filed January 24, 1916. Serial No. 73,993.

To all whom it may concern:

Be it known that I, FRANZ NEUDORF, a subject of the King of Great Britain, and resident of Horndean, in the Province of 5 Manitoba, Dominion of Canada, have invented certain new and useful Improvements in Rail-Joints, of which the following is a specification.

This invention relates to improvements in 10 rail joints and the objects of the invention are to dispense with the use of bolts, to facilitate in holding the rails in alinement, to effectively guard the joint so obviating liability to accident should the rails become 15 slightly displaced, to permit of the rails being easily connected and disconnected, and generally to adapt the several parts to better perform the functions required of them, and it consists essentially of the im- 20 proved construction particularly described and set forth in the following specification and accompanying drawing forming part of the same.

In the drawings,

25 Figure 1 is a perspective view of the improved joint operatively connecting a pair of rails.

Fig. 2 is a perspective view of the im- 30 proved joint as seen when disconnected.

Fig. 3 is a plan view of the same.

Fig. 4 is a transverse section of the im- 35 proved joint.

Like characters of reference refer to like parts in the several figures.

Referring to the drawing, A represents a rail of any usual type and B the improved joint designed to operatively connect adjacent rails together. The joint B comprises 40 a pair of chairs 10 of substantially angle section each formed with an inverted T-shaped recess 11 in its vertical member and provided in the horizontal member with a plurality of orifices 12 through which spikes or the like may be driven to secure the chair 45 to a rail tie.

These chairs are designed to be spaced apart with the inverted T-shaped recesses 11 in alinement so that when the lower flange and web of the rails A are located 50 between the jaws formed by the said recesses the adjacent ends of the rails abut

and are located equidistantly from the said chairs.

The lower member further carries lugs 13 arranged in pairs directly opposite each other and designed to frictionally engage the lower flange of the rails A thereby facilitating in positioning the same.

The rails A are frictionally retained in position by the angle shaped cover straps 60 14 and 15 snugly engaging the flange and web thereof and the edge of the recess 11, the last said strap carrying on its upper edge an offset curvilinear flange 16 located adjacent to but spaced from the lateral face 65 of the rails and bridging the joint thereof so forming a guard adapted to embrace the flange of a car wheel and prevent the same becoming derailed, even when the rails are slightly displaced.

When the chairs are spaced apart, it is 70 essential that creeping of the cover straps 14 and 15 should be eliminated and to this end I provide the lower flange of each strap with a projection 17 located between 75 the chairs 10 and adapted to engage the vertical faces thereof.

In assembling the joint B the rails A are engaged with the inverted T-shaped recesses 80 11 of adjacent chairs whereupon the cover straps 14 and 15 are positioned so that the lower flange is embraced by the lug 13 whereupon the rails are moved in a longitudinal direction so that each cover strap 14 and 15 engages with the rail and the 85 T-shaped recess in the opposite chair and is embraced by the lug 13. The chairs are now secured in position on the tie by driving spikes through the orifices 12.

It will be seen that in a rail joint of 90 this description the rails cannot, under ordinary working circumstances, by any chance become displaced and creeping of the cover straps 14 and 15 is entirely obviated since the projection 17 of the lower 95 flange engages with the vertical member of the chair 10 so securely locking the same in position.

As many changes could be made in the above construction and many apparently 100 widely different embodiments of my invention, within the scope of the claim, con-

structed without departing from the spirit or scope thereof, it is intended that all matter contained in the accompanying specification and drawing shall be interpreted as 5 illustrative and not in a limiting sense.

What I claim as my invention is:

In a rail joint of the class described, a pair of chairs of substantially angle section each provided with an inverted T-shaped 10 recess in the vertical member thereof adapted to engage the web and lower flange of a

rail, lugs on the horizontal member of each chair adapted to embrace the lower flange of the rail, and cover straps located in the T-shaped recess and engaging with the said 15 lugs.

In witness whereof I have hereunto set my hand in the presence of two witnesses.

FRANZ NEUDORF.
